UNITED STATES PATENT OFFICE.

EDWARD P. SHELDON, OF BROOKLYN, NEW YORK, ASSIGNOR, BY MESNE ASSIGNMENTS, TO R. HOE AND CO., INC., OF NEW YORK, N. Y., A CORPORATION OF NEW YORK.

STAPLING MECHANISM.

Application filed September 11, 1924. Serial No. 737,019.

This invention relates to certain improvements in stapling or stitching mechanism, and has been designed particularly for use with printing machines.

In stapling mechanisms, as usually provided for stapling the product from printing machines, a stapling mechanism, usually in the form of a cylinder, a wire supply and stapling horn were provided. An abutment, usually in the form of a roll, was also provided, against which the staples were clenched. These parts took up space, and frequently it was inconvenient to install them in the place desired owing to the press construction, and when installed it was difficult to get at them for adjustment or repair.

Further, where the product is to be collected, a collecting mechanism is necessary, this producing further complications in the press arrangement.

It had been proposed to provide a collecting cylinder with a stapling mechanism, thus eliminating a separate stapling cylinder. With this construction, while very useful under many circumstances, the wire supply and the stapling horn were supported outside the cylinder in separate framing. This arrangement took up space, and in certain circumstances was difficult to install where the collecting cylinder had to be arranged in a certain location in the press. Furthermore, where it was installed, it was often inconvenient or difficult to get at the stapling horn, the wire and the wire feed for adjustment or renewal.

The particular object of the present invention is to provide a unitary staple forming and inserting mechanism in which the wire supply and the staple forming and inserting mechanism are all mounted on one carrier, the parts being arranged so that a small carrier, as a cylinder, may be used, which takes up so little space that it may be positioned at any desired point in the machine.

A further object of the invention is to also provide an organization which will also act as a collecting mechanism and, if desired, one of a pair of cutting cylinders, the staple being clenched against the roll with which the cutting mechanism cooperates to sever the sheets, so that the mechanism is com-

plete in itself and no extra additional cylinders or other parts separate from the cylinder are required.

With these and other objects not specifically referred to in view, the invention consists in certain novel parts, arrangements and combinations which will be described in connection with the accompanying drawings, and the novel features pointed out in the claims annexed hereto.

Referring to the accompanying drawings,

Figure 1 is a side elevation of a unitary cutting, collecting and stapling cylinder in which the wire supply, the staple forming and inserting mechanism, and the cutting and collecting mechanism are all carried by one rotary member;

Figure 2 is a sectional plan view, partly broken away, of one end of the cylinder shown in Fig. 1;

Figure 3 is a vertical sectional view of the mechanism shown in Fig. 2, the section being taken looking in the direction of arrow 3 of Fig. 2, on the irregular line 3—3 of Fig. 2;

Figure 4 is a cross sectional view taken on the line 4—4 of Fig. 3, looking in the direction of the arrow and showing the position of the parts prior to the staple forming operation;

Figure 5 is a similar view showing the position of the parts after the wire has been shaped to form the staple;

Figure 6 is a similar view showing the position of the parts after the staple has been inserted;

Figure 7 is a cross sectional view taken on the irregular line 7—7 of Fig. 3;

Figure 8 is a detail sectional view, the section being taken on the line 8—8 of Fig. 3;

Figure 9 is a detail sectional view taken on the line 9—9 of Fig. 5;

Figure 10 is a detail sectional view taken on the line 10—10 of Fig. 3;

Figure 11 is a side view, on an enlarged scale, showing the wire supply and the method of supporting it;

Figure 12 is a top view of the construction shown in Fig. 11;

Figure 13 is a bottom view of part of the construction shown in Fig. 11, and

Figure 14 is a diagrammatic end view of

the collecting and cutting cylinder and its cooperating abutment.

Referring now to these drawings, the particular machine chosen to illustrate the invention includes a collecting and stapling cylinder, which is also provided with cutting mechanism, and the staple is clenched against the cylinder or roll with which the cutting mechanism cooperates to sever the sheets. It will be understood, however, that the invention is not to be limited to a cutting cylinder, but that it has been designed for use with a mechanism in which the cutting elements are omitted, the staple being clenched against any suitable abutment.

Machines constructed in accordance with the invention, however, will include a rotary carrier provided with a unitary stapling mechanism, and the wire supply will be supported from the carrier, so that the mechanism will include a self contained staple forming and inserting mechanism. While the carrier may vary in construction, in the particular machine chosen to illustrate the invention, this carrier is a cylinder, marked A, this cylinder being supported by shaft heads B and B' suitably journaled in side frames C, which may be the framing of any desired part of the press in which the stapling mechanism is positioned. The particular stapling mechanism shown is capacitated to insert a line of staples in a product, two such mechanisms being indicated generally in Fig. 1 by S and S', and there are provided two wire supplies, two wire feeding mechanisms and operating mechanisms therefor, two staple forming and inserting mechanisms, and operating mechanism for simultaneously operating both of the staple forming and inserting mechanisms. While the wire supplies may be supported in any suitable manner, they are supported on the outside ends of the shaft heads, that is, the ends outside the frames, as shown in Fig. 1. As these mechanisms are duplicates of each other, it will be necessary to describe but one.

Referring now to the left hand end of Fig. 1 and Figs. 11 to 13 inclusive, the wire is supplied from wire rolls 1, these rolls being carried from pins 2 rotatably mounted at one end on a stud 2' secured, as by a set screw 3', in a bracket 3. This bracket is secured to a threaded head 4 screwed onto the shaft or journal 400 of shaft head B, before referred to. The head 4, opposite the bracket 3, is provided with an arm 5 through which the free end of the pin 2 passes. The free end of the pin, beyond the arm, is provided with a groove 6 which engages a latch 7 pivoted on a pin 8 screwed into the arm. The latch 7 is provided, at its rear end, with a notch 9 which receives a projection 10 on a spring 10' secured to the arm, this spring acting normally to keep the

latch in place. With this construction the wire supply is readily accessible, and an expired roll can be removed and a fresh roll inserted with great convenience.

The stapling wire, where wire is the staple material, is drawn off from the spool by suitable feeding mechanism, which may vary to some extent in construction. In machines embodying the best forms of invention, however, where the staple mechanism is a cylinder, the wire forwarding means are located inside the cylinder, and means are provided, adjustable from outside the cylinder, for varying the feeding action of the wire advancing mechanism. As illustrated, the head 4 is formed with a guide channel 11 having a flared outer end 12, this channel projecting through the shaft head B to the interior of the cylinder guiding the wire to the wire advancing mechanism. If desired, the head 4 may be secured on the shaft head B by means of set screws 15. The particular wire advancing mechanism includes an upper guideway 16 (see Fig. 3), a pair of advancing rolls 17, 18, and a lower guideway 13 through which the wire is directed from the advancing means to the staple forming and inserting mechanism. While these rolls may be mounted and operated in various ways, in the particular construction illustrated, the roll 17 is journaled on a stud 19 supported in a bracket 20 secured to the interior of the cylinder. This bracket is provided with an extension 22, in which there is rotatably supported a threaded rod 23, this rod, as shown in Fig. 7, being dimensioned and located so as to project to the outside of the cylinder, the outer end being formed, as shown, with a squared end 23' arranged to receive a suitable tool for rotating the rod, an aperture being left in the cylinder wall around this squared end for the reception of the tool. The stud 19 has secured thereto a driver in the form of a gear 24, this gear meshing with a similar gear 25 carried on a shaft 26 on which the cooperating feed roller 18 is mounted.

One of these rolls is a driven roll, and in the particular construction illustrated the roll 18 is thus driven. In the best constructions, the roll will be driven with a step by step movement, thus effecting an intermittent advancing movement of the wire. While this may be effected in various ways, in the particular construction illustrated, fast on the shaft 26, is a ratchet 27, the ratchet and the gear 25 being secured to the roll by screws 28 (see Fig. 8), the feed roller 18 being fixedly secured on the shaft, as by a key or feather 28'. This shaft 26 (see Fig. 7) is preferably extended outside the cylinder wall so that the wire driving mechanism may be operated without the cylinder by means of a suitable tool, the end of the shaft being squared, as indicated at 26', to receive the tool, the cyl-

inder wall being recessed around the squared end of the shaft to permit ready access to its end. With this construction the feed roll 18 may be operated for testing purposes or feeding in the end of a new wire roll, this operation being effected without changing the relative position of any of the co-operating parts. This shaft 26 is, or may be, supported in any suitable manner, but is in the particular construction illustrated supported in a U shaped bracket 260 (see Fig. 8) suitably secured to a partition 74 referred to hereafter.

The driving gear 25 is operated in any suitable manner to effect an intermittent step by step movement. In the particular construction illustrated, the shaft 26 has journalled thereon a lever arm 30 which carries in one end a pawl 31 which is secured in the arm by a pin 310 and engages the ratchet 27, before referred to. The other end of this lever arm carries a pin 32 which is positioned to engage in an elongated slot 33 formed in the upper end of a lug or projection 34 carried on a slide bar 35. This slide bar is mounted to have a reciprocating sliding movement in the cylinder wall, and is provided with projections 36 which engage slideways 37 formed in the wall of the cylinder and a bracket 38'. This bar is reciprocated to effect the intermittent movement of the driving gear, at the proper time, by means of a cam roll 38 which engages (see Fig. 3) a groove in a cam 39 fast on the shaft head B before referred to.

The staple wire is advanced through the guideway 13 by the movement of the feed rollers, before referred to, so as to lie across a wire supporting member 41 (see Fig. 4), this wire support being provided with a wire receiving groove 40 and acting to support the wire during the staple forming operation. This supporting member is mounted on a rock shaft 42 (see Figs. 4 and 5) which is journalled in projections 43 formed on uprights 44 and 45 which support and guide the staple forming mechanism. These supports are each provided with a pair of guideways 46, 47, 48, 49 (see Fig. 2) and are secured in place, at one end, by being formed on a web 490 secured on the cylinder block or form 491, hereinafter referred to, and at the other end are provided with feet 510 by which they are secured in the cylinder by bolts 50, 51.

The wire support 41 is, at its rear end, provided with a shoulder 52, and the shaft 42 has fast thereon (see Fig. 3) a cam 53. Means are provided by the present invention for locking this wire support 41 in wire receiving and supporting position while the staple is being formed and for moving it out of position to permit the driving of the staple. In the particular construction shown, adjacent the shoulder 52, suitably

secured in the cylinder, is a stud 54 on which is pivoted a latch arm 55 having a latch nose 550 which normally extends over the shoulder 52, as shown in Fig. 4, and holds the wire support in raised position. This latch arm has mounted thereon a stud 56 on which is mounted a cam roll 57. This cam roll 57 is in the path of a cam 58. This cam 58 is fixedly mounted on an operating shaft 59 which extends lengthwise of the cylinder and is journalled in the cylinder block or form 491, before referred to, this shaft 59 being the operating shaft for both the staple forming and inserting mechanisms S and S'. This shaft extends through the shaft head B—B' and carries an arm 600 in which is supported a cam roll 60 running in the groove of a cam 61 loose on the shaft or journal 400 of the shaft head B. This cam 61 is provided with projections 62 (see dotted line Fig. 3) which enter between projections 63 on the hub 630 of a gear 64, also loose on the shaft 400 of the shaft head B. The cam 39, by which the slides 35 are operated, is also secured to the hub of the cam 61 and to the hub 630 of the gear 64, so that these parts can rotate together.

The gear 64 may be locked to the framing C by bolts 65. If an uncollected product is forwarded to the cylinder for stapling, the parts will be, as shown in Fig. 1, locked together, the bolts 65 being in place. When the parts are in this position the cylinder will make one revolution to one operation of the staple forming and inserting mechanism. It will be observed that when the gear is locked to the framing C by the bolts 65, the shaft 400, being driven from the gear 14, will turn freely within the gear hub 630 of the gear 64, the cam 39 and the cam 61, driving the cylinder through the head B, the parts 64, 39 and 61 being stationary. As the cylinder rotates, the roll 60 will be caused by the groove of the cam 61 to operate the stapling mechanism, and the roll 38 turning with the slides 35 will be caused by the groove of the cam 39 to operate the slides, the mechanism functioning to insert the staples at each revolution of the cylinder. If now a collected product is to be produced on the cylinder, the bolts are removed so that the gear 64 can turn and with it the cams 39 and 61. This gear may be placed in mesh with a gear 640 driven in any suitable manner at half the speed of the gear 14 by which the cylinder heads are driven, so that the cylinder will make two revolutions to one operation of the staple forming and inserting mechanism, so that a collected stapled product is produced every two revolutions of the cylinder. It will be observed that when the parts are thus positioned the cams 39 and 61 are driven, thereby shifting the position of the operating surfaces of their cam grooves, so that the cam rolls 38 and 60

120
125
130

60 are operated at every other revolution of the cylinder A, so that the stapling operation takes place only on every other revolution of the cylinder, thus affording time for collecting.

The staple forming and inserting mechanisms are identical and are both operated from the operating shaft 59, before referred to. While this mechanism may be of various characters, in the particular construction illustrated and best shown in Fig. 2, the shaft 59 has secured thereto a forked lever 66 having arms 660, 661 which straddle the plunger guideways 46, 47, 48, 49, before referred to. Each of the side arms 660, 661 of this lever (see Fig. 4) are provided with elongated slots 67 which receive pins 68 which project from the top portion of a pair of staple forming plungers 69, 70, both of which are shown in plan in Fig. 2, and one of which is shown in side elevation in Figs. 4 to 6. These plungers are provided on each side with projections 690 which work into the plunger guideways before referred to.

Means are provided for cutting off a wire length from the wire supply to form the staple. In the particular construction illustrated, this is effected by providing the rear plunger, that is, the plunger next adjacent the wire supply, with a cutting knife 700, this cutting knife being secured to the plunger by screws 701. This knife cooperates with an abutment in the form of a cutting disc 71 (see Fig. 3) suitably secured in the cylinder form below the guideway 13, before referred to, so that as the staple forming plungers are forced downwardly a sufficient length of wire to form the staple will be cut off while the wire is still supported on the wire support 41 and just prior to the bending of the wire to form the staple. These staples forming plungers are provided with grooves 72 (see Figs. 4 and 5) into which the wire is forced, as the staple forming plungers descend, to form the wire into an inverted U shaped staple, and after the wire is thus formed the staple is driven into the product by suitable mechanism which will now be described.

This staple driving mechanism may be varied somewhat in construction, and the abutment against which the staple is clenched may be of various forms. In the particular construction illustrated, however, there is provided a second shaft 73, this shaft extending between and taking bearings in two partitions 74, 74' (see Fig. 1) of the cylinder form. This shaft is, as shown, (see Fig. 2) disposed on the opposite sides of the guideways to the arm 66 and opposite the shaft 59, before referred to. This shaft 73 has secured thereon a lever arm 75 which is arranged to extend over and between the staple forming plungers 69, 70, before re-

ferred to. The outer end of this lever arm is provided with an elongated slot 76 which engages a pin 77 carried on the upper portion of the driving plungers 770. A mechanism is preferably provided whereby the shaft 73 is operated from the shaft 59, before referred to. While these means may vary somewhat in construction, as shown, the lever arm 66 is provided with a lug or projection 78 and the lever 75 is provided with a lug or projection 79, which are secured by means of bolts 790 to a cross-over or connecting bar 80. With this construction the shaft 73 is operated from the shaft 59, and this shaft 73 operates the staple driving mechanism of both stapling mechanisms S and S'.

As the staple forming and inserting movements are exceedingly rapid ones, means are provided for quickly moving the wire support 41 out of the path of the staple clenching plungers as these plungers are operated to drive the staple. In the particular construction illustrated, this is effected (see Fig. 9) by providing one of the wire forming plungers, as plunger 70, with a plate 81 carrying a cam stud 82. This stud runs in the groove 530 of the cam 53 on the shaft 42, before referred to. This cam groove is best shown in dotted lines in Figs. 4 and 5 and is so formed as to be substantially triangular, the high point of the cam 53 being the apex of the triangle. With this construction, as the staple forming plunger descends, it rides in the cam groove until it reaches the high point, when, because of the configuration of the groove, a very quick movement is given to the shaft 42 and the wire support moves out of the way of the staple driving plunger just after the staple has been formed.

In constructions embodying the invention in its best form, this stapling cylinder is also a collecting cylinder, the cylinder being provided with suitable sheet taking devices. While the particular form of sheet taking devices may be varied as desired, in the particular construction illustrated, these sheet taking devices are in the form of pins 84, one of which is shown in dotted lines in Fig. 4, mounted on a shaft 85, which is suitably journaled in the cylinder block 491, and which is actuated by a cam 86. This cam 86 is locked to gear 87, and the cam 39, at the right-hand side of the machine looking at Figure 1, is locked to the cam 86 and the gear 87, the construction by which this is effected being the same as that on the opposite end of the machine, before described. The gear 87 is adapted to be driven at half speed from a gear 88 through the gear 649. When the parts are in the position shown in Figure 1, the pins would operate at every revolution of the cylinder, so that, when not collecting, the pins are silenced, as by remov-

ing the pin points. When, however, collecting is desired, the gear 649 is meshed with the gear 88 and the gear 87 and the pin points replaced, so that the pins are operated together with the stapling mechanism at every other revolution of the cylinder.

The stapling cylinder may also act, if desired, as a cutting cylinder. The form 491 of the cutting cylinder is therefore provided 10 with a socket 90 in which is located a cutting knife 91 and the spring seated cutting cheeks 92, of the usual construction. When the collecting cylinder is utilized as a cutting cylinder the cutting is effected against a co-operating abutment (see Fig. 14) in the form 15 of a cylinder 93 on a shaft 94, this cylinder being provided with the usual cutting woods 95. Where the cylinder is used as a cutting cylinder, the cooperating cylinder 93 may 20 form the abutment against which the staple is clenched and such cylinder is therefore provided with the usual anvil 96. It will be understood that a cylinder such as 93 with an anvil 96 may be used for a clenching abutment whether the stapling cylinder has a 25 cutting element or not, or that any other suitable abutment may be used for effecting the clenching of the staple.

In constructions embodying the invention 30 in its best form, the cylinder is provided with removable walls 97, 98 suitably secured to the form 491, so that if it is desired to get at any interior mechanism of the cylinder this is readily done by removing one of the sections, 35 the section being secured to the form by bolts 99, 100, shown in Fig. 1.

It will be seen with the construction described that a very small cylinder has been provided for perfecting a staple forming or inserting action in which the cylinder acts as a unit, carrying its own wire supply, and that if and as desired this cylinder may also be used as a collecting and cutting cylinder. It will be observed that the cylinder is without 45 a central shaft, the cylinder being supported on the shaft heads, so that a very small cylinder can be used and one which can be positioned in almost any part of the delivery end of a printing machine, wherever 50 it may be desired to position it, great economy in space and in parts being thus effected, as, for instance, it may be placed adjacent the drawing off rolls indicated at D—D', Fig. 14.

55 It is believed that the invention may be readily understood from the foregoing detailed description, but to assist in an understanding of the operation of the machine the following brief statement will be given.

60 The wire is drawn in from the spool at each end of the machine through the wire feeding mechanisms and operated by the slide bars 35 and the cams 39, these wire feeding mechanisms being duplicates. In Fig. 4 the parts 65 are shown in their normal position, that is,

the position they occupy just as a wire length is fed onto the wire support 41. When in this position, the cam 61 operates the shaft 59. This causes the start of the downward movement of the staple forming plungers 70 through the lever 66 to form the staple. As the staple forming plungers move down, the wire length is cut by the cutting knife 700 cooperating with the disc 71, this cutting being effected while the wire is on the wire support 41. A further downward movement of the staple forming plungers forces the wire into the staple forming grooves 72 in the plungers and forms the staple. During this movement the stud 82 travels in the groove 530 of the cam 53 and imparts no motion to the shaft 42 which actuates the wire support 41.

During this movement, however, the cam 58 is acting on the roller 57 of the latch 55 85 and gradually withdrawing it from the shoulder 52 on the wire support carrying shaft 42. This position of the parts is illustrated in Fig. 5, in which it will be seen that the latch is free, and when in this position 90 the staple has been formed. The stud 82 at this time has reached the apex or the high part of cam groove 530, whereupon a very quick rocking action is imparted to the shaft 42 so that the wire support is quickly moved 95 out of the way, leaving a clear path for the operation of the driving plungers. By this time the elongated slot 76 of the lever 75 has reached the limit of its free play and a continuation of the downward movement causes a simultaneous downward movement of the staple forming plunger and the staple driving plunger, so that they both reach the stapling line of the cylinder at approximately 100 the same time and the inserting of the staple 105 in the product is effected against the anvil 96. Just as soon as this is done the parts will return to the position shown in Fig. 4.

While the invention has been illustrated and described in its preferred form, it will 110 be understood that certain changes and variations may be made in the specific structure shown and described without departing from the invention. It will be further understood that the cylinder may be used within 115 the invention either as a stapling cylinder or as a stapling and collecting cylinder, or as a stapling, collecting and cutting cylinder, as may be desired.

What I claim is:

1. In a stapling mechanism, the combination of a rotary cylinder, a pair of heads on which the cylinder is secured at each end, shafts for the heads, staple wire supplies mounted on the shafts outside the heads, means for driving one of the heads, a staple forming and inserting mechanism mounted in the cylinder, sheet taking devices carried by the cylinder, and means for actuating the sheet taking devices.

2. In a stapling mechanism, the combination of a rotary carrier, a wire supply mounted to rotate with the carrier and outside the ends of the carrier, a staple forming and inserting mechanism on the carrier, sheet taking devices on the carrier, and a cooperating abutment.

3. In a stapling mechanism, the combination of a rotary carrier, a wire supply mounted to rotate with the carrier and outside the ends of the carrier, a staple forming and inserting mechanism on the carrier, sheet taking devices on the carrier, a cutting mechanism on the carrier, and a cooperating abutment.

4. In a stapling mechanism, the combination of a rotary cylinder, a pair of heads on which the cylinder is secured at each end, shafts for the heads, staple wire supplies mounted on the shafts outside the heads, means for driving one of the heads, a staple forming and inserting mechanism mounted in the cylinder, a cooperating abutment, sheet taking devices carried by the cylinder, and means for operating the staple forming and inserting mechanism at each revolution of the cylinder or at a predetermined number of revolutions of the cylinder.

5. In a stapling mechanism, the combination of a rotary cylinder, sheet taking devices thereon, a wire supply supported outside the opposite ends of the cylinder and rotating therewith, a staple forming and inserting mechanism mounted in the cylinder, and a cooperating abutment.

6. In a stapling mechanism, the combination of a rotary cylinder provided with sheet taking devices, a cutting mechanism mounted on the cylinder, a wire supply supported outside the opposite ends of the cylinder and rotating therewith, a staple forming and inserting mechanism mounted in the cylinder, and a cooperating abutment.

7. In a stapling mechanism, the combination of a rotary cylinder, a pair of heads on which the cylinder is secured at each end, shafts for the heads, staple wire supplies mounted on the shafts outside of the heads, means for driving one of the heads, a staple forming and inserting mechanism mounted in the cylinder, means for feeding wire to the staple forming and inserting mechanism, a cam for operating the staple forming and inserting mechanism, a cam for operating the wire feeding mechanism, means for causing the operation of the cams at each revolution of the cylinder or at a predetermined number of revolutions of the cylinder, and a cooperating abutment.

8. In a stapling mechanism, the combination of a rotary cylinder, a pair of heads on which the cylinder is supported at its ends, shafts for the heads, a wire supply carried on each of the shafts outside the heads, wire

feeding mechanisms located in the cylinder, a cam loose on each of the shafts for operating the wire feeding mechanisms, a staple forming and inserting mechanism mounted in the cylinder, a cam loose on one of the shafts for operating the staple forming and inserting mechanism, a gear loose on one of the shafts, means for connecting the gear, the cams for operating the staple forming and inserting mechanism and one of the wire feeding mechanisms to run together, and a cooperating abutment.

9. In a stapling mechanism, the combination of a rotary cylinder, a pair of heads on which the cylinder is supported at its ends, shafts for the heads, a wire supply carried on each of the shafts outside the heads, wire feeding mechanisms located in the cylinder, a cam loose on each of the shafts for operating the wire feeding mechanisms, a staple forming and inserting mechanism mounted in the cylinder, a cam loose on one of the shafts for operating the staple forming and inserting mechanism, a gear loose on one of the shafts, means for connecting the gear, the cams for operating the staple forming and inserting mechanism and one of the wire feeding mechanisms to run together, means for causing the cams to operate the mechanisms controlled by them at each revolution of the cylinder or at a predetermined number of revolutions, and a cooperating abutment.

10. In a stapling mechanism, the combination of a rotary cylinder, a pair of heads on which the cylinder is secured at each end, shafts for the heads, staple wire supplies mounted on the shafts outside the heads, means for driving one of the heads, a staple forming and inserting mechanism mounted in the cylinder, and a cooperating abutment.

11. In a stapling mechanism, the combination of a rotary cylinder, a pair of heads on which the cylinder is supported at its ends, shafts for the heads, a wire supply carried on each of the shafts, wire feeding mechanisms in the cylinder, cams on the shafts for operating the wire feeding mechanisms, staple forming and inserting mechanisms in the cylinder, and a cooperating abutment.

12. In a stapling mechanism, the combination of a rotary cylinder, a pair of heads on which the cylinder is supported on its ends, shafts for the heads, a wire supply carried on each of the shafts, wire feeding mechanisms in the cylinder, cams for actuating the feeding mechanisms, staple forming and inserting mechanisms in the cylinder to which wire is delivered, means for adjusting the wire feeding mechanisms from outside the cylinder, and a cooperating abutment.

13. In a stapling mechanism, the combination of a rotary cylinder, a pair of heads on which the cylinder is supported at its ends, shafts for the heads, a wire supply carried

on each of the shafts, wire feeding mechanisms located in the cylinder, a cam on each of the shafts for operating the wire feeding mechanisms, staple forming and inserting mechanisms mounted in the cylinder, a cam on one of the heads for operating the staple forming and inserting mechanisms, and a co-operating abutment.

14. In a stapling mechanism, the combination of a rotary cylinder, sheet taking devices thereon, a pair of heads on which the cylinder is supported at its ends, shafts for the heads, a wire supply carried on each of the shafts, wire feeding mechanisms mounted in the cylinder, a cam on each of the shafts for operating the feeding mechanisms, staple forming and inserting mechanisms in the cylinder, a cam for operating the forming and inserting mechanisms, and a cooperating abutment.

15. In a stapling mechanism, the combination of a rotary cylinder, a pair of heads on which the cylinder is mounted, shafts therefor, wire supplies carried on the shafts, wire feeding mechanisms mounted in the cylinder, each mechanism including a pair of feeding rolls, means for driving the rolls, including a pair of gears, a rod extending through the cylinder wall for adjusting one of the gears, staple forming and inserting mechanisms, and a cooperating abutment.

16. In a stapling mechanism, the combination of a rotary cylinder, a pair of heads on which the cylinder is mounted on each end, a wire supply carried on the heads, a pair of wire feeding mechanisms, each including a pair of feeding rolls, means for driving the rolls by a step by step movement, a slide for actuating the driving means, a cam on the heads connecting with the slide, staple forming and inserting mechanisms in the cylinder, and a cooperating abutment.

17. In a stapling mechanism, the combination of a rotary cylinder, heads at each end of the cylinder for supporting it, a wire supply supported from the heads, wire feeding mechanisms in the cylinder, means for actuating the feeding mechanisms, staple forming and inserting mechanisms capacitated to insert a line of staples in the product, a shaft mounted in the cylinder, means for actuating the shaft to simultaneously operate the staple

forming and inserting mechanisms, and a co-operating abutment.

18. In a stapling mechanism, the combination of a rotary cylinder, a pair of wire feeding mechanisms mounted in the cylinder, means for supplying the wire thereto, a wire receiving support to which a wire length is forwarded, staple forming plungers cooperating with the support to form a staple, staple inserting plungers, means for removing the support from the path of the staple inserting plungers, a shaft, connections between the shaft and the staple forming plungers, a second shaft, connections between the second shaft and the staple inserting plungers, means for operating the shafts, and a cooperating abutment.

19. In a stapling mechanism, the combination of a rotary cylinder, a pair of wire feeding mechanisms mounted in the cylinder, means for supplying the wire thereto, a wire receiving support to which a wire length is forwarded, staple forming plungers cooperating with the support to form a staple, staple inserting plungers, means for removing the support from the path of the staple inserting plungers, a shaft, connections between the shaft and the staple forming plungers, a second shaft, connections between the second shaft and the staple inserting plungers, connections between the shafts whereby the second shaft is operated from the first shaft, and a cooperating abutment.

20. In a stapling mechanism, the combination of a rotary cylinder, heads on which the cylinder is supported at its ends, wire feeding mechanisms in the cylinder, means for supplying wire thereto, a pivoted wire length support to which the wire is forwarded, staple forming plungers cooperating with the support to form a staple, means for severing a wire length from the wire, a shaft actuating the staple forming plungers, a staple inserting mechanism, a shaft for operating the same, means including a cam having a V shaped groove for rocking the wire support out of the path of the inserting mechanism, and a cooperating abutment.

In testimony whereof, I have hereunto set my hand.

EDWARD P. SHELDON.
